UNITED STATES PATENT OFFICE.

CHARLES S. BURNETT, OF PRESIDIO OF SAN FRANCISCO, CALIFORNIA.

PISTON.

Application filed February 8, 1929. Serial No. 338,502.

(GRANTED UNDER THE ACT OF MARCH 3, 1883, AS AMENDED APRIL 30, 1928; 370 O. G. 757.)

This invention described herein may be manufactured and used by or for the Government for governmental purposes, without the payment to me of any royalty thereon.

5 This invention relates to pistons but more particularly it is directed to a piston having a demountable head which is utilized to facilitate the removal of a piston ring, it is also directed to various coordinating features 10 which will be hereinafter set forth in the specifications and claims.

One object of the invention is to provide a removable piston head beneath which a piston ring may be retained, and to provide 15 means for preventing the loosening or detachment of said head due to the reciprocating movement of the piston or the vibrations of the engine, and also to provide a piston head which will retain a ring and hold compression 20 within the cylinder regardless of cracking or splitting of the piston skirt.

Another object of the invention is to provide a piston head which is so constructed as to permit the entrance of gas to the interior 25 of the piston ring and thus expand said ring against the wall of the cylinder. The advantage of a predetermined pressure thus gained being maintained throughout the life of the ring.

30 Still another object of the invention is that the ring is fitted into that portion of the piston nearest the cylinder head thus effecting stoppage of the passage of gas at the most advantageous point.

35 Briefly stated this invention comprises a piston having a removable head in which are cut openings for the admission of gas to the interior and upper surfaces of the adjacent piston ring in order to expand the same 40 against the cylinder wall.

Referring more particularly to the accompanying drawings in which corresponding parts are indicated by similar reference characters.

45 Figure #1 is an isometric sectional view of the piston assembly, the section being taken through the head in such a manner as to show the construction of the slotted openings in the head, and also to show a portion 50 of the head where no slotted opening is located.

Figure #2 shows a fragmentary section of the piston, cut centrally.

Figure #3 shows a modification of the pis-

ton, in which the space for the reception of 55 the lower leg of the angular piston ring, is cut from the body of the piston and not from the head.

Figures #4, and #5 and #6 show several 60 of the different modifications in the construction of piston rings which may be utilized on the piston set forth in this invention.

Figure #7 shows a plan view of the cylinder head.

Figure #8 shows a side elevation of the 65 cylinder head.

In the illustrated embodiment characterizing this invention the numeral 1, designates the main body of the cylinder, 2 the skirt of the cylinder, 3 the hub, and 4 the connecting 70 rod. The numeral 5 designates the cylinder head having slotted openings, 6 which extend the entire depth thereof, and 7 indicates a circumferential cut around the head to accommodate the contour of the piston ring. 75 The piston ring which is designated by the numeral 8 in Figures 1, 2, and 3, is shown to have the shape of a right angle, but in Figures 4, 5, and 6, the piston rings 13, 14 and 15 respectively, have other contours, such as 80 an equilateral triangle, a right triangle, and a rectangle. However these are only a few modifications in the shape of the piston ring, since the head and the cylinder may be cut to accommodate any shape ring which will perform the functions desired. It will be noticed in Figures 1, 2, 5, and 6, that only the cylinder head is cut away to accommodate the contour of the ring; whereas, in Figures 85 3, and 4, both the cylinder head and the body 90 of the cylinder itself are circumferentially cut to accommodate the rings.

The circumferential slots 6 are cut radially with their inner walls 9 sloping outward from the center of the head as they approach the adjacent surface 11 of the body of the piston which underlies the head. The purpose of thus sloping the inner walls 9 is to admit the gas to contact with the piston rings in such a direction that it will cause an outward as 95 well as a downward pressure upon the piston ring and expand the same against the cylinder wall, and also force it downward on its seat.

From the bottom of the cylinder head projects an eccentric portion 12 which is threaded to accommodate itself to similar threads tapped in an eccentrically drilled portion of 100 105

the cylinder body. When the head 5 is screwed to the body by means of the said threaded eccentric projection the circumferential surfaces of both cylinder and head coincide, and the entire piston may then be slipped into the cylinder. The eccentricity of the threaded coupling prevents the unscrewing of the head from the cylinder body due to reciprocatory motion of the piston or 10 the vibration of the engine as stated above.

In assembling the piston it is only necessary to place the ring upon the body of the cylinder and screw on the head until the desired tightness is obtained and the circumferential surfaces of the head and piston body coincide so that the piston may be slid within the cylinder.

As shown in the illustrations, a clearance 16 is allowed between the piston and the ring 20 to permit the entrance of gas, so that the pressure thereof will exert forces downwardly and outwardly upon the piston ring, and press the same against the cylinder wall during various strokes in the cycle of the engine.

While my invention is particularly adapted to be applied to internal combustion engines of any cycle, it will be readily understood that it may be applied to other apparatus such as 30 cylinders of steam engines and pumps and used for other purposes than herein described, and that the arrangements and structural details of my device may be considerably varied from what has been shown and described 35 without altering the mode of operation or departing from the spirit and scope of the invention.

Having described my invention, what I claim as new and wish to secure by Letters 40 Patent is:

1. A piston composed of a body and head portions, means for detachably interconnecting the two portions, said means including an eccentrically mounted boss projecting from the under surface of the head portion, the boss being externally threaded for engagement with an internally threaded opening 45 in the upper surface of the body.

2. A piston composed of a body and head 50 portions, the head portion having peripherally cut slots therein, means for detachably interconnecting the two portions, said means including an eccentrically mounted boss projecting from the under surface of the head portion, the boss being externally threaded for engagement with an internally threaded opening 55 in the upper surface of the body.

3. A piston composed of a body and head 60 portions, the head portion being chamfered on its under surface, and slotted around its periphery, means for detachably interconnecting the two portions, said means including an eccentrically mounted boss projecting from the under surface of the head portion, the boss being externally threaded for en-

gagement with an internally threaded opening in the upper surface of the body, and a piston ring underlying said head between said chamfered portion and the piston.

4. A piston composed of a body and head 70 portion, the head portion being chamfered on its under surface, and slotted at predetermined locations around its periphery, means for detachably interconnecting the two portions, said means including an eccentrically 75 mounted boss projecting from the under surface of the head portion, the boss being externally threaded for engagement with an internally threaded opening in the upper surfaces of the body, and a piston ring underlying said head between said chamfered surface and the piston.

5. A piston composed of a body and head portion, said portions being chamfered respectively on their upper and lower surfaces, 85 and the head portion having radially cut slots located at predetermined locations around its periphery, means for detachably interconnecting the two portions, said means including an eccentrically mounted boss projecting 90 from the under surface of the head portion, the boss being externally threaded for engagement with an internally threaded opening in the upper surface of the body, and a piston ring 95 underlying said head and lying within the chamfered portions of the piston and head.

6. A piston composed of a body and head portion, the head portion being chamfered on its under surfaces, and having peripherally cut slots therein for the admission of gas, means for detachably interconnecting the two portions, said means including an eccentrically mounted boss projecting from the under surface of the head portion, the boss being externally threaded for engagement with an internally threaded opening in the upper surface of the body, and a piston ring surrounding 100 said head and lying within said chamfered portion, so that the gas issuing through said slots may act upon the ring to expand the same.

7. A piston composed of a body and head portion, the head portion being chamfered on its under surface, and having peripherally cut 115 slots, at predetermined locations therein, for the admission of gas, means for detachably interconnecting the two portions, said means including an eccentrically mounted boss projecting from the under surface of the head portion, the boss being externally threaded for engagement with an internally threaded opening in the upper surface of the body, and a piston ring surrounding said head and lying within said chamfered portion with sufficient clearance to permit gas issuing through 120 said slots to exert pressure upon the inner circumferential wall of said ring to expand the same.

8. A piston composed of a body and head 130

portion, the head portion being chamfered on its under surface and having radially cut slots therein at predetermined locations around the periphery, the inner wall of said slots sloping toward the periphery so that openings through the head formed thereby are larger on the upper surface than on the under surface thereof, means for detachably interconnecting the two portions, said means including an eccentrically mounted boss projecting from the under surface of the head portion,

the boss being externally threaded for engagement with an internally threaded opening in the upper surface of the body, and a ring surrounding said head and lying within 15 said chamfered portion with sufficient clearance to permit gas issuing through said peripheral slots to exert pressure upon the inner circumferential wall and upper surface of said ring to expand the same and hold it 20 upon its seat.

CHARLES S. BURNETT.
